(57) **CLAIM**

The ornamental design for a foldable frame for magnifier, as shown and described.

DESCRIPTION

FIG. 1 is a perspective view of a foldable frame for magnifier showing my new design;

FIG. 2 is a front view thereof;

FIG. 3 is a rear view thereof;

FIG. 4 is a right end view thereof;

FIG. 5 is a left end view thereof;

FIG. 6 is a top view thereof;

FIG. 7 is a bottom view thereof.

FIG. 8 is a perspective view thereof, shown in a folded position;

FIG. 9 is a perspective view thereof, showing an in-use condition; and,

FIG. 10 is a perspective view thereof, showing another in-use condition.

The dash-dash broken lines depict portions of the foldable frame for magnifier that form no part of the claimed design. The dot-dot-dash broken lines in FIG. 9 and FIG. 10 depict portions of the environment that form no part of the claimed design.

1 Claim, 10 Drawing Sheets
